UNITED STATES PATENT OFFICE

FRANK MEYER AND OTTO LINK, OF NEW YORK, N. Y.

MOUTHPIECE FOR WOOD WIND INSTRUMENTS

Application filed March 13, 1930. Serial No. 435,590.

This invention relates to mouth pieces for wind instruments such as saxophones, clarinets and the like.

Mouth pieces for instruments of the above type are commonly constructed of metal, in which, it has been recognized by practically all musicians, particularly those who have been engaged in playing such instruments for many years, that the metal of the mouth piece has a deleterious effect upon the teeth of the user, causing the teeth to be worn away along broken and irregular lines, due to the constant engagement of the teeth with the metal surface of the mouth piece. In the endeavor to obviate this disadvantage, attempts have been made to construct mouth pieces for such instruments so that the same would not result in wear upon the teeth. Such attempts in certain instances have been along the lines of providing a cushioning means between the mouth piece and the teeth of the user, on the erroneous assumption that the vibration of the reed has been responsible for the aforesaid deleterious effect of the mouth piece upon the user's teeth. As a matter of fact, it is known by skilled musicians of long experience that the vibration of the reed does not cause the mouth piece to vibrate but that the harmful effects result solely from the rubbing contact between the teeth of the user and the metal of the mouth piece. Where cushioning means have been employed, under the erroneous assumption just stated, the same have been found to be extremely unsatisfactory for several reasons, among which is the fact that in the first place a soft rubber cushion or insert is decidedly unsanitary. In the second place the constant moist condition of the mouth piece tends to cause the soft rubber to deteriorate, whereupon the mouth piece cushion becomes ragged, tending to further irritate the user. In the third place the soft rubber cushion will in time wear out completely. Rubber patches that may be glued on are merely makeshift expedients resorted to for temporary use, and being inconvenient and irritating to the user in themselves necessitate the early replacement of the entire mouth piece.

We have discovered: first, that it is not vi-

bration of the mouth piece that causes wear of the teeth, but rather the rubbing contact of the teeth upon the mouth piece; second, that a mouth piece with a soft rubber insert is not necessary for cushioning purposes, but, 55 rather, has many distinct disadvantages, among which are those already mentioned; and third, that the defects and disadvantages of hard metal and soft rubber mouth pieces, as stated hereinabove, are obviated by constructing the mouth piece with a permanent inlay of hard vulcanized rubber.

The primary object of our invention, therefore, is to provide a sanitary, convenient and non-irritating mouth piece with a tooth engaging inlay, hard in itself, but of less hardness and different texture than the metal of the mouth piece body whereby the wearing effect upon the teeth is eliminated, 70 the tooth engaging inlay being practically non-wearing, so that the smooth outline of the mouth piece body can be maintained practically throughout the life of the mouth piece, thereby promoting uniformity in the relation between the mouth piece of the instrument and the teeth and lips of the player, as well as obviating the disadvantages of rapid-wearing germ-carrying soft rubber inlays.

Other objects and advantages of the invention will be hereinafter specifically pointed out, or will become apparent, as the specification proceeds.

With the above indicated objects in view, the invention resides in certain novel constructions and combinations and arrangement of parts, clearly described in the following specification and fully illustrated in the accompanying drawings, which latter 90 show embodiments of the invention as at present preferred.

In the drawings:

Fig. 1 is a longitudinal top plan view of a mouth piece constructed according to my invention.

Fig. 2 is a side elevation of same.

Fig. 3 is a partial longitudinal sectional view taken on the line 3-3 of Fig. 1.

Fig. 4 is a partial perspective view show-

100

ing the end of the mouth piece before vulcanization of the hard rubber inlay therein.

The mouth piece may be of practically any conventional form, including a tubular body 10 with a neck portion 11 for connection with the instrument and a tip 12 to be received by the mouth of the player. The lay surface 13 of the tubular body 10 is provided with the usual vibrating reed 14, the butt end 15 of which may be secured in place by means of a ligature 16.

The upper surface of the mouth piece tip 12 is formed with a transversely extending recess 17 in that portion of the tip which is usually disposed in alignment with the teeth of the user. The recess 17 may be of any desired depth and in this instance has substantially vertical forward and rearward walls 18 and 19 respectively, these walls extending to the upper surface of the mouth piece tip 12 which is slightly convex in contour. This recess 17 is adapted to receive an inlay of rubber and to secure the same permanently therein during the process of vulcanization. To finally hold the hard rubber inlay 20 in place within the recess 17, we find it advantageous to form a plurality of horizontal bores 21 and 22 extending from the recess 17 into the walls 18 and 19 respectively.

In producing the hard rubber inlay, a mass of soft rubber is placed in the recess 17 and subjected to pressure during the vulcanization operation. This causes the rubber to enter the bores 21 and 22 so that the inlay 20 includes a plurality of hard integral projections 23 and 24 which extend into the bores 21 and 22, the construction and arrangement of these projections 23 and 24 enabling the inlay to be permanently secured within the recess 17. After vulcanization, the inlay is finished off to conform to the desired outline of the finished mouth piece and after the inlay has been polished, the entire mouth piece may be plated with gold or other metal as may be desired.

The hereinabove described construction admits of considerable modification without departing from the invention; therefore, it is 50 the wish not to be limited to the precise arrangements shown and described, which are as aforesaid, by way of illustration merely. In other words, the scope of protection contemplated is to be taken solely from the appended claims, interpreted as broadly as is 55 consistent with the prior art.

What is claimed is:

1. A mouthpiece for wind instruments including a tubular metallic body having a tip 30 adapted to be received by the lips of the user, said tip having a transversely extending recess, said recess having substantially vertical forward and rearward walls, said walls including a plurality of substantially horizontal bores, and a hard rubber inlay se-

cured in said transverse recess, said inlay having a plurality of integral projections extending into said bores whereby to permanently secure said inlay in place upon said tip.

2. A mouthpiece for wind instruments including a metallic body portion having a tip adapted to be received by the lips of the user, said tip having a recess extending across its upper part, said recess having forward and rearward walls, each of said walls having a plurality of separated substantially horizontally extending bores, and a vulcanized hard rubber inlay secured in said transverse recess, said inlay including a plurality of hard integral projections extending into said bores whereby to permanently secure said inlay in place upon said tip, the sides of said inlay extending downwardly below the upper surface of said tip.

In testimony whereof we hereby affix our signatures.

OTTO LINK,
FRANK MEYER.
